Primary Examiner — Robin V Webster*Assistant Examiner* — Rachel Voorhies(74) *Attorney, Agent, or Firm* — McAndrews, Held & Malloy, Ltd.(57) **CLAIM**

The ornamental design for a display screen or portion thereof with graphical user interface, as shown and described.

DESCRIPTION

The FIGURE is a front view of a display screen or portion thereof with graphical user interface showing my new design.

The dash-dash broken lines around the FIGURE show a display screen or portion thereof, which forms no part of the claimed design; the dash-dash broken lines within the FIGURE show unclaimed portions for the graphical user interface. The dot-dash broken lines within the FIGURE represent an unclaimed boundary line that forms no part of the claimed design.

1 Claim, 1 Drawing Sheet(56)
